UNITED STATES PATENT OFFICE.

EDWIN A. LOUGEE, OF HAVERHILL, MASSACHUSETTS, ASSIGNOR, BY MESNE ASSIGNMENTS, TO THE UNITED SHOE MACHINERY COMPANY, A CORPORATION OF NEW JERSEY.

MEANS FOR DETAINING OR RELEASING TOP LIFTS IN HEEL-NAILING MACHINES.

SPECIFICATION forming part of Letters Patent No. 707,143, dated August 19, 1902.

Application filed June 10, 1898. Renewed April 19, 1900. Serial No. 13,515. (No model.)

To all whom it may concern:

Be it known that I, EDWIN A. LOUGEE, of Haverhill, in the county of Essex and State of Massachusetts, have invented an Improvement in Means for Detaining or Releasing Top Lifts in Heel-Nailing Machines, of which the following description, in connection with the accompanying drawings, is a specification, like letters on the drawings representing like parts.

In heel-nailing machines it has been customary to apply a heel-holder and a top-lift holder to a plate which is swung so that it occupies at times a proper position to place a heel above the nail-block, and the heel having been attached the plate is moved to place a top lift under the heel, so that at the next rise of the usual die-bed spindle the top lift will be spanked onto the protruding nails 15 extending somewhat from the tread end of the heel. The top lift is usually thin, and in the lateral movement of the plate holding it the top lift is liable to be disturbed or to escape from its holding devices, and to overcome this difficulty I have added to the back gage of the top-lift holder a detaining and releasing device, it serving to detain and then at the proper time to release the top lift.

Figure 1 is a top view of a plate having a heel and top-lift holder, the latter being provided with my improvement. Fig. 2 is a partial under side view of Fig. 1. Fig. 3 is a detail in side elevation of part of a lever instrumental in actuating the top-lift detaining and releasing device, said lever having a guide. Fig. 4 is a section in the line x , Fig. 1.

The plate A and forked gage a to receive the rounded rear end of the heel, the breast-gage a' to act on the breast of the heel, the forked gage c to receive the rounded end of the top lift, the breast-gage c' to act upon the breast of the top lift, the said breast-gages being controlled by suitable springs, as d d' , the said plate having a fixed stud e , which 45 serves as a pivot, and a roller e' , which is acted upon when it is desired to turn the plate A to place either the heel or the top lift above or in line with the vertical movement of the die-bed spindle, are and may be all substantially as usual in heel-nailing machines. The

plate A constitutes a support for the back gage and other operative parts. In accordance with my invention the stud e has been prolonged above the top of the plate, and I have mounted upon it a lever f , having its short end f' recessed to constitute a guide to receive loosely a link f^2 , the long end of said lever (see Fig. 1) being provided with a suitable roller f^3 . The stud e has secured upon it above said lever a toe g , and above the toe the stud is surrounded by a spring g' , one end of which is connected with said toe, while the other end acts against a part of the lever f , said spring normally acting to keep one side of said lever against a stop h , extended from a block h' , applied to the stud e , said block being recessed, as shown, to receive and surround the spring g' . To the stud e above the block h' I apply a washer m and above it a nut m' .

The link f^2 is connected by a suitable pin n with the short arm of a lever n' , pivoted at n^3 , said lever having some teeth, as at n^4 , which engage with other teeth n^5 of a second lever n^6 , pivoted at n^6 , said teeth causing said levers to move toward and from each other in unison when the lever n' is moved by or through the link f^2 .

The forked or back gage c to receive the rear end of the top lift lies close to and just above a part of the plate A, so that the top lift laid upon the plate may have its rounded rear edge pushed into the said fork, the breast-gage c' keeping it in the fork.

The levers n' and n^6 constitute what I have designated as a "top-lift detaining and releasing device," and normally they occupy the position shown by full lines in Figs. 1 and 4—that is, they overhang the inner edges of the fork c , so that the rounded end of the top lift is pushed, as it might be considered, into a sort of a box; but just as the top lift is to be spanked upon the heel the roller f^3 meets some fixed or movable part of the heelng-machine and is pushed laterally into the position shown by dotted lines, such movement of the lever f resulting in separating the top lift detainer into its dotted-line position, Fig. 1, so that the edges of said detainer no longer overlap a portion of the top lift, leaving it free to be 100

pressed firmly against the heel-seat end of the heel, and as the die-bed spindle is again lowered the top lift holder and detainer retire from the heel, and in its final descent the lever *f* under the control of the spring *g'* is moved into its full-line position, thus causing the inner edges of the lever constituting the top-lift detainer to again cross and overlap somewhat the inner edges of the fork or back gage of the top-lift holder.

Having described my invention, what I claim as new, and desire to secure by Letters Patent, is—

- 15 1. A back gage and a support therefor, combined with a detainer and means to actuate it that said detainer may at times overlap part of the space of the back gage and at other times be moved to uncover said space.
- 20 2. A back gage to receive the rear end of a top lift, and a support for said gage, combined with a detainer to overlap the edge of the back gage and a top lift therein, and means to open said detainer to effect the release of a top lift.
- 25 3. A top-lift back gage, a support therefor, and levers operatively connected together and constituting a top-lift detainer, combined with means to actuate said levers in unison to release the top lift.
- 30 4. A top-lift back gage, a support for said gage, and two levers pivoted on said back gage and operatively connected together to constitute a top-lift detainer, combined with means to actuate one of said levers, causing both of said levers to be moved in unison toward and from each other.
- 35 5. In a machine of the class described, a top-

lift carrier, means for positioning a top lift on the carrier, a detainer extending over the top lift, and means to withdraw said detainer 40 before the top lift is spanked onto a heel.

6. A pivoted plate, a forked back gage for a top lift, a breast-gage acting against the breast of a top lift, means moving with said plate and operating automatically to retain 45 the top lift temporarily in the back gage, and means to turn the top-lift-retaining means to release the top lift when it is to be spanked on an attached heel.

7. The plate A provided with means for 50 holding a heel, and means having a back gage for holding a top lift; a lever pivoted above said plate and provided with a guide; and a link in said guide; combined with a top-lift detaining and releasing mechanism operatively connected with said link, said mechanism co-operating with the back gage of the top-lift holder, to at times overlap and hold, and to then release the top lift.

8. A back gage, and a support therefor, 60 combined with a detainer located above and acting to partially cover the space in said back gage, a device connected with said detainer and means to actuate said device to move said detainer in a horizontal plane to 65 uncover the space in the back gage.

In testimony whereof I have signed my name to this specification in the presence of two subscribing witnesses.

EDWIN A. LOUGEE.
